UNITED STATES PATENT OFFICE.

ROBERT P. LITTLE, OF COLUMBUS, OHIO.

WINDOW-SASH FASTENER.

1,395,047.

Specification of Letters Patent. Patented Oct. 25, 1921.

Application filed December 23, 1920. Serial No. 432,651.

To all whom it may concern:

Be it known that I, ROBERT P. LITTLE, a citizen of the United States, residing at Columbus, in the county of Franklin and State 5 of Ohio, have invented certain new and useful Improvements in Window-Sash Fasteners, of which the following is a specification.

This invention relates to improvements in window sash fasteners, and has for its object 10 to provide a simple, inexpensive and efficient fastening device adapted to be employed in combination with the upper and lower sashes of a window construction for the purpose of locking said sashes together and to prevent 15 relative movement thereof.

In carrying out the invention, use is made 20 of a bearing plate which is adapted to be rigidly secured to the upper surface of a lower window sash, and to which is pivotally connected a vertically oscillatable fastening arm, the latter being provided with 25 a locking extremity capable of entering a recess in one of a plurality of keeper plates which are adapted to be rigidly secured to the upper sash of the window construction, 30 the construction being such that when the arm is oscillated so that its locking extremity is received within the recess of one of said keeper plates, the two sashes will be locked together and relative movement therebetween effectually prevented.

Another object of the invention resides in providing the outer end of the fastening arm with a device for positively locking such 35 arm in connection with any one of the keeper plates, said device comprising a resilient depressible finger which is so disposed that when the locking extremity of said arm initially enters the recess of the 40 keeper plate, said finger will contact with a beveled surface formed with the keeper plate, and will be depressed so as to be crowded downwardly against the upper surface of the locking extremity of the fastening 45 arm, whereby when said arm is fully positioned within said recess, said finger will register with a pocket provided in the keeper plate in communication with its recess, the arrangement being such that accidental releasing movement on the part of 50 the arm will be precluded, or in other words, said arm cannot be moved to an unlocking position until after the finger has been depressed manually to release the same from 55 coöperation with said pocket. A further object of the invention resides in forming the

locking extremity with a downwardly beveled lower surface, which is designed for co-operation with a correspondingly beveled surface provided upon the lower wall of the 60 bottom of said recess, the arrangement being such that the locking extremity will be securely held within said recess so that the sashes cannot be pried laterally to disengage the locking extremity from its position 65 within the recess.

Other objects of the invention reside in producing a sash fastener which is convenient and simple to operate, of but few parts and not likely to become out of order, and 70 formed in such manner as to constitute a sturdy and staunch construction which may be effectively used in resisting unnatural efforts to relatively operate the window sashes.

For a further understanding of the invention, reference is to be had to the following description and to the accompanying drawing, in which similar characters of reference denote like and corresponding parts 80 throughout the several views thereof.

In said drawing:

Figure 1 is a fragmentary perspective view of a pair of window sashes and illustrating the application of the sash fastener 85 comprising the present invention thereto.

Fig. 2 is a vertical sectional view taken through the sash construction and illustrating the fastener in side elevation.

Fig. 3 is an enlarged detail sectional view, 90 illustrating more particularly the relationship between the locking elements of the fastener, and,

Fig. 4 is a detail vertical sectional view taken along the line 4—4 of Fig. 3.

Referring more particularly to the details of the invention, the numeral 1 designates generally a standard form of window construction, the type commonly employed in conjunction with habitable dwellings. As 100 usual, this construction includes spaced sash guides, in which are mounted for vertical relative movement upper and lower window sashes 2 and 3 respectively. In combination with these sashes, use is made of a fastening structure 4 which is designed with the view of firmly locking said sashes together and to prevent the latter from being forced or improperly raised or lowered and also with the view of performing the objects above recited.

In its preferred form, the fastening struc-

ture 4 makes use of a bearing plate 5, which is preferably located upon the upper surface of the lower sash 3 and at each side of the latter, only one of such plates, however, being illustrated. The plate 5 includes a circular base 6, which is securely connected with the upper surface of the lower sash by means of suitable fastening elements, such for example, as ordinary 10 wood screws 7. Arising from the plate 5 is a pair of spaced integral lugs or bearings 8, which are provided with alining apertures, through which a horizontal pivot pin 9 is adapted to extend and to be suitably 15 secured.

Pivottally mounted upon the pin 9 and capable of oscillating vertically thereabout is a fastening arm 10, the construction of which being such that its lower end will 20 be provided with a bore capable of receiving the pin 9 and to be capable of freely rotating thereabout. The arm extends angularly and outwardly toward the upper sash 2 and may be of any suitable length, however, its upper portion terminates in a relatively offset locking extremity or nose 11 which, when the arm is swung to assume a substantially upright position, will be received within an open-sided recess 12 provided in locking or keeper plates 13.

The keeper plates 13, as shown, are mounted upon the inner surface of the vertical rails 14 of the upper sash 2 and are locked in vertical alinement and spaced 35 relationship upon both of the rails of said upper sash, whereby upon moving the sash relatively, the locking extremity 11 of the arm 10 may be slidably positioned within any one of the recesses of said keeper plates 40 so that said sashes may be locked at any desired position of relative adjustment. The keeper plates are preferably formed from metal and are secured in position upon the upper sash by means of one or more securing 45 screws 15, which operate to securely connect said plates 13 in applied and properly distributed positions upon the upper sash. The recess 12 provided in said keeper plates have their open sides disposed toward the 50 inner portions of the sash, whereby upon oscillating the arm 10, the extremity 11 thereof will be permitted to enter said recesses. It will be observed that the under portion or surface of the extremity 11 is 55 downwardly and outwardly beveled as at 16, and similarly, the lower wall of each of the recesses 12, is upwardly and inwardly beveled as at 17 to correspond with the beveled face of the extremity 11 when the 60 arm 10 is in an active locking position. By this construction a double locking effect is secured, to-wit, the sashes are prevented from being moved vertically and also laterally, a feature which prevents the sashes 65 from being pried apart to remove the lock-

ing extremity 11 from its position within the recess 12, a condition which might be effected if the beveled surfaces 16 and 17 were not provided.

Under certain circumstances, it has been 70 found advisable to positively lock the extremity 11 within the keeper plate recesses 12. Mainly, this is done in order to prevent the parts from becoming accidentally disengaged, and to render the operation of the 75 lock certain and effectual. To this end, the upper or outer surface of the arm 10 is provided with a leaf spring 18, or its equivalent. This spring is bent so as to produce a base portion 19, which is fastened by means 80 of a screw 20 to the arm 10. From its point of connection with the arm 10, the spring is bent upon itself as at 21 so as to produce an outwardly extending resilient portion 22, which terminates in a locking finger 23. 85 Normally, by reason of the inherent resiliency of the spring 18, the finger 23 is maintained in spaced relation from the extremity 11, however, when the arm 10 is swung to assume an active locking position and initially enters the open side of one of the recesses 12, the finger 23 will contact with a sloping or beveled surface 24 provided in conjunction with said recess. This engagement between the finger 23 and the surface 90 24 results in crowding said finger downwardly into the depression 25 provided in the extremity 11, while the arm 10 is being depressed toward its final locking position. When this final locking position is reached, 100 the finger 23 moves upwardly, by reason of the resiliency of the spring, and will be confined and positioned within a pocket 26, formed in each of said plates in communication with the recesses 12 thereof. The registration of the finger 23 and the pocket 26 is automatically effected by the contacting of the outer side of the arm with the closed end 105 of the recess 12. Manifestly, by this construction, it will be impossible for the locking members to become accidentally separated, since such separation can only be effected after the portion 22 has been manually depressed to effect the release of the 110 finger 23. When this is done, the arm may be swung inwardly of the sash construction so as to clear the plates 13, hence permitting of relative movement on the part of the sashes. It will be observed that the arm 10 is of sufficient length so that its locking extremity will clear the rail construction 14 of the upper sash, when said arm assumes an 115 inactive position, thus allowing the sashes to be moved relatively without interference.

From the foregoing description, taken in 125 conjunction with the accompanying drawing, it will be apparent that the present invention provides a sash fastener of simple yet efficient construction and one capable of practical use in its particular field. The fas- 130

tener is formed of but few and simple parts, may be conveniently and easily operated and will serve to resist to the utmost extraneous efforts to effect the raising and lowering of 5 its correlated sashes.

In particular fields, certain minor features of construction, combination and arrangement of parts may necessitate deviations from the exact structure above described, however, it will be understood that such alterations may be hereinafter effected provided that the same fall within the scope and intent of the following claims. 10

What is claimed is:

15 1. A sash fastener comprising a base plate adapted to be carried by the upper surface of the lower of a pair of window sashes, a fastening arm pivotally connected with said base plate and capable of swinging on a ver-

20 tical arm, a locking extremity provided upon the outer end of said arm, a keeper plate adapted to be carried by the upper of said sashes, and said keeper plate including an open sided recess capable of receiving and 25 retaining the locking extremity of said arm.

3. A sash fastener comprising a base plate formed to be secured to the upper surface of the lower of a pair of window sashes, a fastening arm having its lower portion pivotally connected to said plate, whereby said arm may be swung vertically, an offset locking extension provided upon the outer end of said arm, a plurality of keeper plates arranged to be carried in vertically spaced 30 relationship by the side rails of the upper of said sashes, and said keeper plates being provided with open sided recesses capable of selectively receiving the locking extremity of said arm when the latter is swung to 35 assume a locking position.

3. A sash fastener comprising a vertically oscillatable arm constructed to have its lower end pivotally connected with the upper surface of the lower of a pair of sashes, a locking extremity provided upon the outer end of said arm, and the keeper plate having an open sided recess carried by the upper of 45 said sashes, said recess being capable of receiving the locking extremity of said arm when the latter is moved upwardly and outwardly to hold said sashes in locked relationship. 50

4. A sash fastener comprising a vertically movable locking arm, a pivotal connection 55 between the lower end of said arm and the upper part of the lower of a pair of sashes, an offset locking extremity provided upon the outer end of said arm, said extremity having its lower surface downwardly and outwardly beveled, a keeper plate arranged to be fixed to the side of the upper of said sashes, said keeper plate being provided with an open sided recess capable of receiving the locking extension of said arm, and 60 the lower wall of said recess being upwardly 65

and inwardly beveled to conform with the inclination of the bottom surface of said extension.

5. A sash fastener comprising an arm arranged to be pivotally carried for vertical 70 swinging movement by the upper surface of the lower of a pair of sashes, a locking extension provided upon the outer end of said arm, a rib projecting downwardly from the lower portion of said extension, a keeper 75 plate arranged to be carried by the side of the upper of said sashes, said keeper plate being provided with an open sided recess capable of receiving said locking extension, and a second rib provided upon the lower wall of said recess and coöperative with the rib of said locking extension to prevent lateral movement between said arm and plate. 80

6. A sash fastener comprising an arm arranged to be pivotally carried by the upper surface of the lower of a pair of window sashes, a locking extension provided upon the outer portion of said arm, a keeper plate arranged to be fixed to the side of the upper 90 of said sashes, said keeper plate being provided with an open sided recess capable of receiving said locking extension, and a resilient member carried by the outer end of said arm and coöperative with said keeper plate to positively lock said arm in connection with said plate. 95

7. A sash fastener comprising an arm arranged to be pivotally carried by the upper surface of the lower of a pair of window 100 sashes and capable of being vertically oscillated, a locking extension provided upon the outer end of said arm, a keeper plate fixed to the upper of said sashes, said plate being provided with an open sided recess 105 and a communicating pocket, and a resilient member mounted upon the outer end of said arm and capable of being seated within said pocket to prevent movement on the part of said arm when said locking extension is fully positioned within said recess. 110

8. A sash fastener comprising a pivotally mounted arm arranged for vertical movement upon the upper surface of the lower of a pair of window sashes, a lateral extension integrally formed with the outer end of said arm, a keeper plate having a recess formed therein, said recess being capable of receiving said locking extension to hold said sashes against relative movement, a resilient member carried by the outer end of said arm, and a beveled surface provided on said plate contiguous to the entrance of said recess, said beveled surface being disposed to engage with said resilient member when said arm is swung to assume an active locking position, whereby said member will be depressed, and said plate being further formed with a pocket disposed adjacent to the inner end of said beveled sur- 115 120 125 130

face, and said pocket being arranged to receive said resilient member to maintain said arm in locked engagement with said plate.

9. A sash fastener comprising a base plate arranged to be carried by the upper surface of the lower of a pair of sashes, integral apertured ears projecting upwardly from said base plate, a horizontal pin secured in the apertures of said ears, a locking arm having its lower end provided with a bore arranged to receive said pin, whereby said arm may be oscillated vertically, said arm

being angularly and outwardly inclined and having its outer end terminated in a lateral locking extension, a keeper plate having an open sided recess arranged to receive said locking extension when said arm is swung upwardly and outwardly, and a resilient finger carried by the outer end of said arm and co-operative with a pocket provided in said keeper plate for holding said arm against undue movement.

In testimony whereof I affix my signature.
ROBERT P. LITTLE.
